UNITED STATES PATENT OFFICE.

HERBERT HENRY BERRY, OF LONDON, ENGLAND.

IMITATION-FIRE.

1,336,500.

Specification of Letters Patent. Patented Apr. 13, 1920.

Application filed November 23, 1917. Serial No. 203,648.

To all whom it may concern:

Be it known that I, HERBERT HENRY BERRY, a citizen of the United Kingdom of Great Britain and Ireland, and resident of 5 the Switch House, 86 Newman street, London, W., England, have invented certain new and useful Improvements in Imitation-Fires, of which the following is a specification, such as will enable others skilled in 10 the art to which it appertains to make and use the same.

This invention relates to electric and gas "fires" of that kind in which one or more lamps or burners are fitted behind a screen 15 or cover formed of transparent and opaque materials and in some forms of which the heat from the said lamps or burners is employed to rotate devices which produce a flicker effect as viewed from the front of 20 the "fire."

It is important that the "fuel" *i. e.*, the transparent and opaque material shall represent coal or coke in as realistic a manner as possible, and for that purpose I employ 25 blocks of glass in combination with blocks of opaque material, which may be coal or coke or the like and mount the said blocks of glass and the opaque material upon a guard or frame which is placed over the 30 lamps or burners in such a manner that the light therefrom will be seen through the blocks of glass. The said blocks of glass, and if desired the opaque material, may be secured to the guard or frame so that they 35 may be moved therewith, or they may simply be assembled thereon in any convenient manner.

The blocks of glass may be colored and they, and also the opaque material may be 40 provided with reflecting surfaces, say pieces of tinsel or other material, or coatings which will enhance the "fire" effect.

A preferred form of the blocks of glass is obtained by breaking up ordinary glass 45 skimmings, that is to say skimmings from furnaces in which glass is ordinarily made, and which in a general way is commercially a waste product. These skimmings are often only partly crystallized and variously 50 colored, so that they are partly clear and partly semi-transparent in which condition, by a selection of pieces I obtain material, which with a light behind it has very much the appearance of glowing coal or coke.

55 The frame which supports the "fuel" may also carry the lamp or burner fittings,

so that the whole of the "fire" may be moved as a unit and taken from one fireplace to another.

In the accompanying drawings Figure 1 60 is a sectional view of one form of my invention as applied to an ordinary fireplace.

Fig. 2 is a front elevation of a like 65 fitting and Fig. 3 is an illustration of the invention as carried out in brazier form.

Referring to Figs. 1 and 2 the invention herein illustrated, comprises a portable frame 1 over the front of which blocks of colored glass 2 and blocks of coal 3 are placed. Within this frame, two electric 70 lamps 4 are fitted so that the heated air rising therefrom will rotate fans 5 which carry depending strips 6. The light from these lamps is thrown outwardly through the blocks 2 and is given a flickering effect 75 by the rotation of the fan 5 and its strips 6. The drawing shows one lamp only, the other being directly behind it, and because the fans are set so as to rotate in opposite directions, the flickers are made in two directions and as seen from the front are thoroughly intermingled. This intermingling effect is enhanced by the mirrors 7. An electric heater 8 is hung upon the front bars 9 of the stove.

80 Referring to Fig. 3 the brazier 10 contains wire frame 11 supporting the colored glass and the coal blocks as in Figs. 1 and 2. In this case, the two lamps 12 and 13 with their oppositely rotating fans 14 and 15 are 90 clearly seen. Mirrors 16 are also employed here and an electric heat radiator 17 encircles the brazier as shown. This radiator may be of any suitable kind such as the usual wire resistance commonly used for 95 electric radiators.

Either or both the blocks of glass and the opaque material may be treated in any way to improve the effect, such for example as by partly covering them with fine 100 material for example, coal dust or coke dust.

What I claim and desire to secure by Letters Patent is:—

1. In imitation fires, a supporting frame, blocks of fuel supported by the said frame, and illuminating element within the frame and protected thereby, and diagonally disposed mirrors carried by the said frame to reflect the illumination through the fuel blocks.

105 2. In imitation fires, a frame, fuel blocks supported thereby, an illuminating member

supported within the frame, and a reflecting device extending diagonally of a lower corner of the frame for reflecting light through the fuel blocks.

- 5 3. Imitation fuel for fires comprising blocks of glass and pieces of opaque material in combination with a support for said block and pieces, a pair of lights positioned behind said support, a pair of thermally operated fans between said lights and

support, said fans being adapted to rotate in opposite directions, so that the flickers are thoroughly intermingled and mirrors for enhancing the intermingling effect.

In witness whereof I have hereunto set 15 my hand in presence of two witnesses.

HERBERT HENRY BERRY.

Witnesses:

DOROTHY McATAMNEY,
HENRY FAIRBROTHER.
